KEY CASE AND KEY THEREFOR

Homer N. Olsen, Ogden, Utah

Application August 26, 1949, Serial No. 112,625

11 Claims. (Cl. 70—456)

1

The present invention relates to key cases and particularly to a key case adapted to retain a plurality of keys therein and including means for selecting and ejecting a desired key for use.

The primary object of the invention is to provide a key case in which a number of keys can be stored in a small space and in which a desired key can be selected by the sense of sight or touch and released for use by depression of a selector slide.

Another object of the invention is to provide a key case having a plurality of channels in which a number of keys can be stored in predetermined order, the keys being slidable in the channels to a projected position of use, in which the keys are retained in stored position by magnetic attraction and a selector is provided for mechanically locating a desired key by sense of sight or touch and releasing the same from the stored position for use.

Another object of the invention is the provision of a key case having channels for storing a plurality of keys and in which a selected key after release from the stored position may drop to the bottom of its channel with the key end of the shank projecting from the case and be locked in such position for use.

A further object of the invention is the provision of a key case in which a key after use may be caused to return to stored position and be automatically retained in said position until it is positively ejected for further use.

A further object of the invention is to provide a novel key member adapted for use in the key case according to the invention.

The invention is embodied in a key case comprising a casing in which are provided a plurality of slots or channels adapted slidably to receive a key, means is provided for releasably retaining the keys in stored position in the respective channels and a selector means is provided for ejecting a selected key from the retaining means so that it can slide in its channel to a projected position for use.

Other objects and advantages of the invention as well as the details of construction of a preferred embodiment of the invention will become apparent during the course of the following specification and reference to the accompanying drawings forming a part thereof.

In the drawings:

Fig. 1 is a side elevation, partly in section of a key case embodying the invention.

Fig. 2 is a section taken on the line 2—2 of Fig. 1, and

Fig. 3 is a bottom end view, partly in section, Fig. 4 is a top end view, and

Fig. 5 is a perspective view of one of the key members.

Referring now more particularly to the draw-

2

ings, the key case according to the invention comprises a flat, generally rectangular case or body 5 provided with a plurality of longitudinally extending open ended key channels or slots 6, defined by transverse parallel partition walls 7. Each of the walls 7 carries a longitudinally extending rib 8 which projects into its respective key channel and terminates short of the lower end thereof for a purpose presently to be described.

At the lower end of the casing, each of the partition walls 7 is formed with an arcuate bearing flange 9, which with the lower end of the ribs 8, which are cut off on an arc as a continuation of the arc of the flanges 9, form an arcuate bearing for a circular lug or boss 10 on the side of each key member 11 at the base end thereof.

The key members according to the invention consist of a headless shank adapted to be retained in engagement with the case by cooperation of the lugs 10 thereof with the bearing flanges 9 so that the body of the case serves as a handle for the keys when the latter are released to slide to a projected position for use.

Instead of having the usual enlarged head which serves as a handle in ordinary keys, the key 11 is made substantially the same width from end to end thereof and with the straight back edge extending throughout its length so that it rests against the back wall of the key channel when the key is in position to slide therein. Due to the elimination of enlarged head ends on the key members the key case can be made very small and compact while still holding a goodly number of keys.

One key member 11 is disposed in each of the key channels 6 with the lug 10 facing the partition wall thereof carrying the rib 8 and the lug 10 is cut away at one side to provide a flat face 12 adapted to engage and slide along said rib, as more clearly indicated in Fig. 2. When a key member is dropped to the bottom of its channel, the lug 10 engages the arcuate bearing wall 9 to prevent the key from passing completely out of the channel and the lug may turn in the bearing formed by the flange 9 because in this position, the flat face 12 of the lug is clear of the lower end of the rib 8. One side wall of the casing 5 is slotted at its lower end at 13 to accommodate the shank of the key when the latter is rotated to a position at ninety degrees to the axis of the channels.

It will be noted that when the lug 10 seats on the arcuate bearing flange and the key is pivoted slightly out of alignment with its channel, the flat face 12 on the lug also moves out of alignment with the rib 8 and the circular periphery of the lug engages the lower end of the rib, thereby locking the key in the lower projected position so that end pressure thereon will not move it out of this position. The key can

only be returned to retracted position in the channel when it is vertically aligned with the channel and the flat face 12 is in position to ride up on the rib 8.

The keys are releasably retained in retracted position housed within the casing 5 by means of a permanent magnet 14 which extends across the top of all of the channels 6. The magnet 14 is in the form of an inverted U-shaped bar and is seated at its ends on upstanding shoulders 15 carried by the end wall partitions of the case, the shoulders 15 extending between the sides of the magnet at the ends and holding it rigidly in position. In order that the magnet 14 will attract and retain the keys in retracted position when they are moved within its range, the keys 11 or the lugs 10 may be made of magnetic material. In practice it is preferred that the lugs 10 be made of soft iron or other suitable magnetic material, as it is usually the practice to make the key shanks of brass.

The keys are released from engagement with the magnet by means of a combined selector and ejector slide 16 in the form of a fork which straddles the magnet 14 and the legs 17 of which project slightly into the upper ends of the channels 6 when the same is in retracted position. The ejector 16 is provided with a knob or handle 18 which projects through an elongated slot 19 in the upper end wall of the casing, which is in the form of a removable cap 20, and is resiliently held in retracted position by a longitudinal spring bar 21 which extends through the fork thereof above the magnet 14. The ends of the spring bar 21 are turned downwardly at its ends and formed into coil springs 22 which are anchored in the upper ends of the shoulders 15 beyond the ends of the magnet 14.

As stated above, the prongs or legs 17 of the selector slide 16 are long enough to project slightly into the upper ends of the key channels so that they are too long to permit free sliding motion of the slide back and forth along the tops of the partitions 7. Therefore, when the knob handle 18 of the slide is moved laterally to shift the slide, the same first tilts and depresses the spring bar 21 until the ends of the legs slide up and over the top of the adjacent partition 7 into the next key channel. This operation is accompanied by a visible movement and a click that is discernible to both the sense of hearing and the sense of touch. Therefore, with the various keys disposed in known positions in the case, the user, knowing how many partitions the slide has passed, knows over which key the selector rests. By simply moving it to the channel housing the key desired and depressing the knob 18, the selected key will be moved by engagement of the ends of the legs 17 therewith out of the range of the lines of force of the magnet 14 and will fall to the bottom of the channel where it is stopped by engagement of the lug 10 with the end bearing flange 9. If the key case is then rotated clockwise from the position shown in Fig. 2, the key and lug being integral rotate and the key becomes locked in projection position ready for use with the case acting as a handle.

When it is desired to return the key to stored position, the case is rotated counterclockwise to align the key with the channel in which position it can slide freely into the channel and the case is upended to cause the key to slide by gravity into the channel and engage the magnet again.

In this manner any key in the case can be mechanically located by the sense of touch, caused to

fall to the bottom of the case, locked in position for use and be returned to its stored position in the case.

While a preferred construction and mode of operation of the invention has been shown and described by way of illustration, it will be understood that various modifications in the details of construction and operation may be resorted to without departing from the principles or spirit of the invention within the scope of the appended claims.

I claim:

1. A key case comprising a casing, means providing a plurality of key slots in the casing each adapted to slidably receive a key having an end portion of magnetic material, a magnet mounted in said casing across one end of said slots to retain the keys therein by magnetic attraction and means mounted in the casing for selectively disengaging the keys from the magnet.

2. In combination, a key case comprising a casing having a plurality of key channels therein, a key member in each channel, each key member being formed at least in part of magnetic material and having a bearing lug at one end adapted to slide in said channel, said casing having a slot adjacent an end of each channel for passing the key member and a bearing for receiving and retaining said bearing lug at the last mentioned end of each of said channels, a magnet mounted in said casing adjacent the other end of said channels to releasably retain the keys therein by magnetic attraction and means for selectively releasing the keys from engagement with the magnet.

3. In combination, a key case comprising a casing having a plurality of key channels therein, a key member in each channel, each key member being formed at least in part of magnetic material and having a bearing lug at one end adapted to slide in said channel, said casing having a slot adjacent one end of each channel for passing the key member and a bearing for receiving and retaining said bearing lug at the last mentioned end of each of said channels, a magnet mounted in said casing adjacent the other end of said channels to releasably retain the keys therein by magnetic attraction and means for selectively releasing the keys from engagement with the magnet, comprising a depressible spring retractable ejector member slidably mounted in said casing and adapted to be aligned with a selected key to be released.

4. In combination, a key case comprising a casing having a plurality of key channels therein open at one end thereof, a longitudinal rib projecting into said channel, a key member freely slidably in each of said channels and adapted to be housed therein, a substantially circular bearing lug carried by each of said key members at the base end thereof and having a cut away portion adapted to seat on said rib, means providing an arcuate bearing wall at the open end of each of said channels for receiving and retaining said lugs when the key members are shifted to projected position, said ribs terminating short of said bearing walls to permit rotation of said bearing lugs on said arcuate bearing walls when the cutaway portion of said bearing lugs clears the ends of said ribs, means adjacent the other end of said channels for releasably retaining the key members therein and means for selectively releasing the key members from said retaining means.

5. In combination, a key case comprising a cas-

ing having a plurality of key channels therein open at one end thereof, a longitudinal rib projecting into said channel, a key member being formed at least in part of magnetic material and freely slideable in each of said channels and adapted to be housed therein, a substantially circular bearing lug carried by each of said key members at the head end thereof and having a cut away portion adapted to seat said rib, means providing an arcuate bearing wall at the open end of each of said channels for receiving and retaining said lugs when the key members are shifted to projected position, said ribs terminating short of said bearing walls to permit rotation of said bearing lugs on said arcuate bearing walls when the cutaway portion of said bearing lugs clears the ends of said ribs, a magnet mounted in said casing adjacent the other end of said channels to releasably retain the keys therein by magnetic attraction and means for selectively releasing the keys from engagement with the magnet.

6. In combination, a key case comprising a casing having a plurality of key channels therein open at one end thereof, a longitudinal rib projecting into said channel, a key member being formed at least in part of magnetic material and freely slideable in each of said channels and adapted to be housed therein, a substantially circular bearing lug carried by each of said key members at the head end thereof and having a cut away portion adapted to seat said rib, means providing an arcuate bearing wall at the open end of each of said channels for receiving and retaining said lugs when the key members are shifted to projected position, said ribs terminating short of said bearing walls to permit rotation of said bearing lugs on said arcuate bearing walls when the cutaway portion of said bearing lugs clears the ends of said ribs, a magnet mounted in said casing adjacent the other end of said channels to releasably retain the keys therein by magnetic attraction and means for selectively releasing the keys from engagement with the magnet, comprising a depressible spring retracted ejector member slidably mounted in said casing and adapted to be aligned with a selected key to be released.

7. In combination, a key case comprising a casing having a plurality of key channels therein, a key member in each channel, each key member being formed at least in part of magnetic material and having a bearing lug at one end adapted to slide in said channel, said casing having a slot adjacent one end of each channel for passing the key member and a bearing for receiving and retaining said bearing lug at the last mentioned end of each of said channels, a magnet mounted in said casing adjacent the other end of said channels to releasably retain the keys therein by magnetic attraction and means for selectively releasing the keys from engagement with the magnet, comprising a depressible spring retracted ejector member slidably mounted in said casing and adapted to be aligned with a selected key to be released, said depressible ejector having an end portion normally extending into the end of said channels and slideable over the edges thereof from channel to channel as said member is slid to a position over a selected key channel whereby a desired key can be selected by the sense of touch.

8. In combination, a key case comprising a casing having a plurality of key channels therein open at one end thereof, a longitudinal rib projecting into said channel, a key member being

75

formed at least in part of magnetic material and freely slideable in each of said channels and adapted to be housed therein, a substantially circular bearing lug carried by each of said key members at the head end thereof and having a cut away portion adapted to seat said rib, means providing an arcuate bearing wall at the open end of each of said channels for receiving and retaining said lugs when the key members are shifted to projected position, said ribs terminating short of said bearing walls to permit rotation of said bearing lugs on said arcuate bearing walls when the cutaway portion of said bearing lugs clears the ends of said ribs, a magnet mounted in said casing adjacent the other end of said channels to releasably retain the keys therein by magnetic attraction and means for selectively releasing the keys from engagement with the magnet, comprising a depressible spring retracted ejector member slidably mounted in said casing and adapted to be aligned with a selected key to be released, said depressible ejector having an end portion normally extending into the end of said channels and slideable over the edges thereof from channel to channel as said member is slid to a position over a selected key channel whereby a desired key can be selected by the sense of touch.

9. In combination, a key case comprising a casing having a plurality of key channels therein, a key member in each channel, each key member being formed at least in part of magnetic material and having a bearing lug at one end adapted to slide in said channel, said casing having a slot adjacent one end of each channel for passing the key member and a bearing for receiving and retaining said bearing lug at the last mentioned end of each of said channels, a magnet mounted in said casing adjacent the other end of said channels to releasably retain the keys therein by magnetic attraction and means for selectively releasing any key from engagement with the magnet comprising a manually depressible selector movable over the ends of the key slots.

10. In a device of the character described, a headless key blank consisting of a shank and a bearing lug of magnetic material on one face thereof at the end opposite the insertion end of said shank, the periphery of said lug being circular except for a flat portion extending parallel to the longitudinal axis of said shank.

11. A key member adapted for use in a key case of the character described, comprising a headless shank having a straight back edge extending substantially from end to end thereof parallel to the longitudinal axis of said shank and a bearing lug of magnetic material on one face thereof at the end opposite the insertion end of said shank, the periphery of said lug being circular except for a flat portion extending parallel to the longitudinal axis of said shank.

HOMER N. OLSEN.
